UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,607, dated August 28, 1894.

Application filed August 3, 1894. Serial No. 519,381. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of ornaments with ornamental scrolls diverging from said ornaments upwardly on opposite sides of said ornaments and connected above said ornaments forming panels, with a group of birds and foliage in the center of said panels as represented in the accompanying drawing. A 10 heraldic form of shield ornaments connected by said ornamental scrolls form part of the design as shown. The border or upper por-

tion of the design is formed of ornamental scrolls forming panels with birds and foliage in the center of said panels and heraldic or 20 shield ornaments connecting said panels as shown in the drawing.

What I claim is—

1. The design for wall paper herein shown and described.
2. In the design for wall paper, the border herein shown and described.

Witness my hand this 31st day of July, 1894.

CHARLES BOOZE.
